UNITED STATES PATENT OFFICE

SAMUEL RUBEN, OF NEW YORK, N. Y., ASSIGNEE, BY MESNE ASSIGNMENTS, TO RUBEN
TUBE COMPANY, OF NEW YORK, N. Y., A CORPORATION OF DELAWARE

VACUUM-TUBE APPARATUS

Application filed February 4, 1922. Serial No. 534,213.

This invention relates to vacuum tube apparatus; and it relates more particularly to an improved type of vacuum tube apparatus in which an electron emission element dis- 5 charges electrons through an evacuated space to a plate element that is responsive to or affected by electron impact in a manner utilizable to produce certain important results of novel and highly useful character.

10 The ordinary vacuum tube or thermionic relay commonly used at present comprises essentially three elements, namely, (a) a source of electron emission, usually a filament heated to incandescence, constituting a 15 cathode element; (b) a modulating device in the form of a grid adapted and arranged to control emission and to cause variations thereof; and (c) a plate or anode element to which the emission from the filament or cathode 20 element discharges. In the ordinary vacuum tube device the plate or anode element functions simply as an electrode upon which the electrons are discharged from the filament and from which the space current flows to the 25 said filament or cathode element.

I have discovered that the efficiency and sensitiveness of vacuum tube devices of this general type, such as an electron relay, can be materially increased by proper utilization 30 of the kinetic energy of the electrons and ions (if any) composing the discharge, which kinetic energy has been dissipated and wasted in such devices heretofore. The said kinetic energy or energy of electron impact upon the 35 plate element manifests itself in such forms as (a) low wave length light radiation, (b) heat of impact, (c) mechanical pressure due to impact, (d) secondary electronic and ionic emission due to impact.

40 It is therefore a principal object of the invention to utilize these several effects of the electron discharge in such manner as to increase the efficiency and sensitiveness of devices of this general description. This object is attained in accordance with the present 45 invention broadly by employing a plate or anode element that is usefully responsive to such effects of electronic impact; and also, in the most desirable embodiment of the invention, by employing such an anode in con-

junction with a special type of filament or other emission element operating at substantially lower temperature than that of the incandescent filament ordinarily employed; a modulating element or grid being also 55 ordinarily included in the combination and serving to respond to variations in an operatively associated circuit, such as a radio telegraph or telephone circuit, or the like, thereby to modulate and control the electron stream in the evacuated chamber of the relay device for the purpose of obtaining a 60 suitable current in the relay circuit.

The plate or anode element of vacuum tube apparatus constructed in accordance with the 65 principles of this invention may take various forms provided it is responsive to the effects of electron impact as above pointed out. In one desirable practical embodiment of the invention, the anode or plate element is a 70 selenium cell. In conjunction with the selenium cell anode element, there is most desirably employed as the cathode or source of electron emission an oxide coated filament which operates at a low red heat, the advantage of utilizing a filament of such properties residing in the fact that such a filament 75 has in itself less effect upon the special anode than would an incandescent filament of the usual type. Between the said anode and 80 cathode elements is interposed any suitable form of modulating grid.

In order to afford a full understanding of the principles of the invention, one embodiment thereof in an especially desirable practical form is illustrated in the accompanying drawings and is hereinafter described in detail for the sake of a concrete illustrative example; but it is to be understood that the invention is not limited to this particular arrangement or specific type of apparatus.

In the drawings referred to, Fig. 1 is a more or less diagrammatic representation of a vacuum tube device constructed in accordance with the present invention, the view being a central section with certain parts shown in elevation;

Fig. 2 is a view of the selenium cell plate or anode element viewed at right angles to Fig. 1;

Fig. 3 is a circuit diagram illustrating the employment of the novel device as an electron relay in a radio receiving system.

Referring first more particularly to Figs. 1 and 2, 10 is an evacuated glass tube or bulb in which are suitably mounted the electron emission element or cathode 11, the plate element or anode 12, and the modulating grid 13. In the present example the electron emission element 11 consists of an oxide-coated filament operating effectively at low red heat. The plate or anode element is of such character as to be responsive to some or all of the effects of electron impact, especially the effects hereinabove specifically referred to; and in the present example said anode consists of a selenium cell of the well known Bidwell type, a selenium cell being especially well adapted for the purpose. Generally described, a selenium cell of this type and as here illustrated consists of a grooved porcelain body 14, upon which are wound two copper wires that are spaced apart from each other, the windings being indicated generally at 15 and the separate leads to the respective insulated windings being indicated at 16 and 17 and shown extending out through stem 18 of the evacuated tube. The spaces between the separated copper wire windings 15 are filled with metallic selenium. The cell is suitably supported, in this instance by bracket member 19 and clamp 20, upon the insulating rod or standard 21, formed integrally with the stem 18. The leads 22 and 23 to the filament 11, and the lead 24 to the grid or modulating device pass through the stem 25 of the evacuated tube in the usual manner.

The selenium cell forming the plate or anode element in the construction above described serves admirably for the purposes of the invention because the impact of the electron stream from the filament against the cell reduces the cell resistance materially by reason of the mechanical pressure of electron impact upon the cell, the low wave length light radiation produced, and the heating effect upon the cell. A thermo-electric current is also produced as a result of the heating effect of the impact, and there is also a secondary emission discharge at right angles to the electron stream by potential across the cell. It is to be noted that all these factors act in the same direction or cumulatively; so that when the relay circuit is influenced by some other circuit, such as a radio receiving circuit, through the agency of the modulating device or grid, a large response is caused in said relay circuit. Furthermore the response due to the peculiar character of the anode or plate element can be added to or superimposed upon the effect or response obtained with the ordinary electron relay device of the type heretofore in use.

While a selenium cell is especially desir-

able in practice to employ as the plate or anode element, particularly because of its negative thermal coefficient of resistance, any other device responsive to some or all of the various effects produced upon the anode by the vacuum tube discharge can be utilized to realize the benefits of the invention in whole or in part. Among other devices utilizable in this connection may be mentioned general types such as a photo-electric cell, a sensitive thermo-electric couple, and a sensitive high resistance. A selenium cell such as that here illustrated embodies the characteristic functions of all three of these types, however, as already explained. Moreover, the invention is not limited to the employment of a heated filament as a source of electron emission or cathode element which may consist of any type of element of such character or so operated as to produce such emission either with or without the use of heat.

Fig. 3 illustrates in simple form an application of the invention to a radio receiving system, where the primary circuit includes the antenna 26 and the variable primary 27 of the oscillation transformer connected to ground as shown, the variable condenser 28 being connected across the primary inductance. The primary 27 energizes the secondary 29 of the transformer, across which is connected the variable condenser 30, and variations in potential in the oscillatory circuit thus constituted are impressed through condenser 31 upon the grid or modulating device 13 of the electron relay device hereinabove described in detail. The filament 11 is heated by the battery B_1 , the heating circuit including the variable resistance R . The grid is connected, as shown, to the negative side of battery B_1 . At B_2 is the driving battery of the plate circuit. In addition, there is what may be termed a secondary plate circuit, in this instance the selenium cell circuit, which as here shown includes the battery B_2 , and a translating device such as a telephone receiver T , interposed between said battery and the selenium cell. It will be seen that current flow in this secondary selenium cell circuit fluctuates with changes in the selenium cell resistance, which changes result from variations in the electron stream flow effected by the grid. Referring to the operation in detail, it will be seen that when the filament 11 is heated to a dull red heat, it supplies electrons and ions which are discharged to the selenium cell plate, causing a change in the current of the cell circuit due to the effect of their impact upon the surface of the cell. When the normal potential of the grid 13 is altered by potential impressed upon it from the tuned secondary receiving circuit 29, 30, this causes variation in the volume of the electron stream; and by reason of this variation is produced a varia-

tion of enhanced amplitude in the secondary plate or cell circuit. In the circuit arrangement shown, variations in both the primary (emission discharge circuit) and the secondary anode (cell) circuit are added together or superimposed one upon the other to give resultant variations of still greater amplitude which produce correspondingly intense audible signals in the telephone T.

In my prior co-pending application Serial No. 418,896, filed October 23, 1920, which matured on May 3, 1927, into Patent No. 1,627,411, I have disclosed and claimed an electron relay device in which the varying mechanical pressure effect produced by the impact or bombardment of the varying electron stream is utilized by employing a vibratory plate element responsive to such impact or bombardment, specifically the diaphragm of a microphone transmitter, the resultant vibrations of which, acting upon a carbon granule, produce variations in a battery-energized secondary plate circuit analogous to that hereinabove described. The present application is therefore an improvement on the device of said prior co-pending application; and it is to be understood that the type of apparatus disclosed in said prior application is included within the scope of certain of the broad claims hereto appended. While the device of said prior application thus embodies certain of the broad principles underlying the present improvements, it is not so efficient because it does not utilize the impact effect of electron emission to such an extent, and the present apparatus is accordingly deemed superior in practice.

In explaining the principles of the invention, reference has been made more particularly to an electron relay acting as an oscillation detector; but it is to be understood that the invention can be embodied in vacuum tube apparatus employed for other purposes such, for example, as apparatus for generating radio frequency currents.

What I claim is:

1. Vacuum tube apparatus comprising an evacuated chamber containing an oxide-coated filament constituting a cathode element, and a selenium cell constituting an anode element.
2. In a vacuum tube device, the combination, with an electron emission element, of a cooperating anode element comprising a selenium cell.
3. An electron discharge device including an evacuated receptacle, a filamentary cathode in said receptacle, and a selenium coated anode in said receptacle for cooperation with the cathode.
4. In a vacuum tube device, the combination, with an electron emission element, of a cooperating selenium-coated anode element.
5. Vacuum tube apparatus comprising an evacuated chamber containing an oxide-coat-

ed filament constituting a cathode element, and a selenium coated anode element.

6. A vacuum tube device containing an incandescent filament of high electron emissive properties at low luminosity, and a co-operating double terminal anode electrically responsive to light rays.

7. A space discharge device comprising a selenium coated anode member and an oxide coated incandescent filament, said filament being adapted to high electronic emission at low luminosity.

8. A photo-electric cell comprising a selenium coated anode member and an oxide coated incandescent filament, said filament being adapted to high electronic emission at low luminosity.

9. An electron discharge device comprising an evacuated receptacle, a cathode in said receptacle, and a selenium coated anode in said receptacle in close proximity to the cathode and extending in spaced parallel relation thereto.

10. In an amplifying device a cathode, a grid for varying the stream of electrons emitted by said cathode, and a two terminal light responsive anode having a negative temperature coefficient of resistance.

11. In an amplifying device a cathode adapted to operate at luminous temperature, a grid for varying the intensity of the electron emission from said cathode, and a two terminal anode designed to have a current flow therethrough and being sensitive to variations in the intensity of radiations from the cathode including light to affect the current flow therein.

12. An anode composed of spaced conductors normally electrically disconnected and bridged by material responsive to energy variations to vary the electrical conductivity of said anode.

In testimony whereof I hereunto affix my signature.

SAMUEL RUBEN.
